UNITED STATES PATENT OFFICE.

JULIUS BARTHEL, OF MILWAUKEE, WISCONSIN.

WRIST-PIN.

SPECIFICATION forming part of Letters Patent No. 434,236, dated August 12, 1890.

Application filed June 2, 1890. Serial No. 353,958. (No model.)

To all whom it may concern:

Be it known that I, JULIUS BARTHEL, of Milwaukee, in the county of Milwaukee, and in the State of Wisconsin, have invented certain new and useful Improvements in Wrist-Pins; and I do hereby declare that the following is a full, clear, and exact description thereof.

My invention relates more particularly to those wrist-pins that are employed as a means of connection between the main shaft crank and piston of a steam-engine; and it consists in certain peculiarities of construction and combination of parts to be hereinafter described with reference to the accompanying drawings, and subsequently claimed.

In the drawings, Figure 1 represents an elevation, partly in section, and illustrates my improved wrist-pin in connection with a crank; Fig. 2, an end view of the wrist-pin without its cap. Fig. 3 is a rear elevation of the cap, and Fig. 4 a front elevation of said wrist-pin.

Referring by letter to the drawings, A represents a shaft, B a crank fast thereon, and C my improved wrist-pin fitted to the crank. The wrist-pin has the outer end of its body portion provided with a screw-threaded stem D, and this stem may be engaged by a tapped opening in said body portion of the wrist-pin, as shown, or the latter may be turned down to form said stem. In addition to the stem D, the outer end of the body portion of the wrist-pin is provided with lugs E, and the latter may be integral with said body portion of the wrist-pin or provided with screw-threads for engagement with tapped openings therein, the latter construction being the one illustrated. The lugs E engage openings in washers F, that surround the stem D, and slipped onto this stem is a cap G, that engages the body portion of the wrist-pin and impinges against the piston-rod (shown by dotted lines, Fig. 1) or pitman thereon. The cap G is provided with recesses b for engagement with the lugs E, and held in place against the washers F by means of a set-nut H on the screw-threaded stem D, and the set-nut is locked in its adjusted position by means of a check-nut I, that is also arranged on said stem. By the arrangement of the lugs E and washers or packing F the latter is prevented from turning on the adjacent stem. In case

the piston-rod or pitman has loose lateral play on the wrist-pin the cap G is detached from the stem D and a certain amount of the packing formed by the washers F removed, after which said cap is replaced on said stem and forced in by the nut H as far as possible on the body portion of the wrist-pin C, whereby said piston-rod or pitman is brought snug against the crank B of the shaft A and the loose lateral play overcome. This is of especial advantage in connection with steam-engines, as it prevents pounding of the piston due to loose lateral play of its rod on the wrist-pin.

Having thus described my invention, what I claim as new, and desire to secure by Letters Patent, is—

1. A wrist-pin having one end thereof provided with a stem, a cap slipped onto the stem, a packing interposed between the cap and adjacent end of the wrist-pin, and suitable means for clamping the cap against the packing, substantially as set forth.

2. A wrist-pin having one end thereof provided with a screw-threaded stem, a cap arranged on the stem, a set-nut also arranged on said stem to oppose the cap, and a packing interposed between the said cap and adjacent end of the wrist-pin, substantially as set forth.

3. A wrist-pin having one end thereof provided with a screw-threaded stem, a cap, set-nut, and check-nut arranged on the stem, and a packing interposed between the cap and adjacent end of said wrist-pin, substantially as set forth.

4. A wrist-pin having one end thereof provided with a stem and lugs, a cap slipped onto the stem and provided with recesses for engagement with the lugs, a packing engaging the lugs and stem between the cap and wrist-pin, and suitable means for clamping said cap against the packing, substantially as set forth.

In testimony that I claim the foregoing I have hereunto set my hand, at Milwaukee, in the county of Milwaukee and State of Wisconsin, in the presence of two witnesses.

JULIUS BARTHEL.
